UNITED STATES PATENT OFFICE.

JOHN BACON SMITH, OF AYLMER, CANADA.

NON-REUSABLE BOTTLE.

SPECIFICATION forming part of Letters Patent No. 783,549, dated February 28, 1905.

Application filed July 22, 1904. Serial No. 217,666.

To all whom it may concern:

Be it known that I, JOHN BACON SMITH, bookkeeper, of the village of Aylmer, in the county of Ottawa, Province of Quebec, Canada, have invented certain new and useful Improvements in Non-Reusable Bottles, of which the following is a specification.

My invention relates to improvements in non-reusable bottles; and the objects of my invention are to devise a bottle of cheap and simple construction and such that when once opened and the contents thereof emptied it will not be possible to use it for the original purpose again; and it consists, essentially, of 15 a bottle having a circumferential weakening groove cut in the neck thereof, a suitable stopper of cork or other material adapted to be inserted below the groove, an auxiliary tapered glass stopper provided with an upper flange, a circumferential recess near the bottom thereof, and a flange below the recess, 20 an annulus of rubber or other suitable material, preferably rectangular in cross-section, adapted to fit in the said recess and lock the 25 auxiliary stopper in the neck of the bottle by engaging the circumferential groove in the neck of the bottle, the various parts of the device being constructed as hereinafter more particularly described.

Figure 1 is a sectional view of the neck of the bottle in perspective, showing my improvements. Fig. 2 is a perspective view of the auxiliary glass stopper, part being broken away and in section to more clearly show the 35 construction thereof.

In the drawings like letters of reference indicate corresponding parts in each figure. *a* is the body of the bottle, and *b* is the neck thereof. A circumferential groove is provided at *c* for purposes hereinafter explained. A similar groove may be cut in the outside of the bottle, (shown at *d*), whereby the neck is made very thin at that point and so the top portion *e* above the groove may be easily 45 broken off. The bore of the neck above the groove is slightly larger than below in order to permit of the easy insertion of a cork below the groove.

f is a stopper of cork or other suitable material placed in the neck below the groove.

g is an auxiliary glass stopper located in the bottle above the groove. The cross-section of the stopper diminishes from the top to the bottom. A circumferential recess *h* is provided near the bottom of this stopper, a flange *i* extending below the recess. This flange is made exactly to fit the bore of the bottle above the groove. On top of the stopper is provided another flange, *j*, which is adapted to engage the top of the bottle when the stopper *g* is inserted. This flange prevents the insertion of a knife or other instrument to cut the washer, and so withdraw the stopper without mutilating the bottle.

k is a annulus made of rubber or other suitable material, preferably rectangular in cross-section. Part of this annulus is adapted to fit in the recess *h*, the remaining portion extending outwardly and engaging a circumferential groove in the neck of the bottle after the stopper has been inserted.

The manner of using the bottle is as follows: The liquid having been poured into the bottle, the ordinary cork *f* is inserted. The auxiliary glass stopper is then inserted, the rubber annulus *k* having previously been placed in the recess *h*. This auxiliary stopper is forced down until the annulus *k* engages the circumferential groove *c*. It will then be impossible to remove the stopper, since the flange *i* is of exactly the same diameter as the part of the bottle above the groove. It will thus be seen that the only way of opening the bottle and obtaining the contents thereof is to strike the portion of the bottle above the groove a sharp blow, which will break that portion of the bottle off. The cork *f* may then be withdrawn and the contents used. As the bottle is destroyed in opening, it cannot be used for the same purpose again.

It will thus be seen that I have devised a useful, cheap, and simple non-reusable bottle. The uses to which such a bottle could be put are numerous. Firms desiring to protect their own liquid manufacture may do so by using these bottles, whereby competitors will not be able to reuse the bottles containing their manufacture.

It is to be understood that I do not wish to limit myself to the exact details of construc-

tion herein set forth, as certain variations may be made therein without departing from the spirit of my invention.

What I claim as my invention is—

5 In a non-reusable bottle, the combination with the body, stopper and neck thereof provided with a circumferential weakening-groove, of an auxiliary stopper having a flange extending over the neck of the bottle at the 10 top thereof, and a circumferential weakening-groove near the bottom thereof, the said stopper being tapered from the said flange to the

said recess, and an annulus of rubber or the like adapted to fit in the recess and lock the stopper in the neck of the bottle by engaging 15 the circumferential groove therein as and for the purpose specified.

Signed at Ottawa, Ontario, this 18th day of July, 1904.

JOHN BACON SMITH.
